DISPLAY APPARATUS

Joseph Taddonio, East Boston, Mass.

Application June 17, 1937, Serial No. 148,716

6 Claims.

(Cl. 40—32)

This invention pertains to improvements in display apparatus and relates more particularly to devices of the type in which a flexible band or web, bearing display characters, figures or symbols of light-obscuring type, is caused to move between a light source and the observer, so that the display characters or the like appear to move across the field of vision. The present invention pertains more especially to improvements in the flexible band and in means for storing that portion of the band or web which for the time being is not exposed to the view of the observer.

Quite commonly the flexible band is of fine-woven, substantially opaque cloth and the display characters or the like, (for instance a series of consecutive letters spelling a word or words) are formed by perforating the outline of each letter in the material of the band. The band is usually quite thin in order to secure the desired flexibility, but as the band is subjected to very sharp flexure and substantial pulling stress when packing it into and withdrawing it from the storage chamber, the bands are not very durable,—showing a marked tendency to crack or tear along the lines of the closely spaced perforations which form the outlines of the display characters. Consequently these bands must frequently be replaced or at least repaired.

It is to be noted that when it is desired to change the display characters, for example to substitute a new advertising slogan or the like, the entire band must be removed and a new one prepared and put in place. Moreover, the making of such a band requires a considerable degree of skill and care, for since each character is outlined by perforations through the substance of the band, it is manifest that error on the part of the operator,—for example, errors in spelling, word arrangement, punctuation or the like, results in a defect not easily remedied. As the band is usually one integral length of material and of very substantial extent, it is almost certain that improperly formed or located characters will occur somewhere in the length of the band.

A principal object of the invention is to provide a flexible display band or web which is strong and durable,—capable of withstanding sharp flexing and the stresses imposed in forcing it into and withdrawing it from the storage chamber,—and in particular to provide a band or web of such a construction that the characters, symbols or other display elements may readily be changed without necessitating replacement of the entire band or web, and such that the setting up of the desired words or other characters or devices to be

exhibited is greatly facilitated and may be so accomplished as to permit ready correction of error.

In apparatus of the above type, wherein the display band or web is far longer than the field of view, that portion of the band or web which has been exhibited is continuously packed or piled as a folded mass into a storage chamber while other portions of the band are at the same time being withdrawn from the chamber for re-exhibition. However, as above noted, this operation subjects the band or web to sharp flexings and to substantial tensile stress, and tends to cause rapid wear and breaking along the lines of perforations which form the letters or symbols. Since the band, in accordance with the present invention, may be somewhat heavier than the usual band, it is subjected to even greater stress in dragging it through the storage chamber.

A further object of the present invention is to provide means for moving the massed, folded band through the storage chamber so as to reduce the pull imposed on the band necessary to draw it along, and thus to reduce the tensile stress to which the band is subjected, and at the same time to reduce the power consumed by greatly reducing the friction of the massed band upon adjacent parts.

Other and further objects and advantages of the invention will be made manifest in the following more detailed description and by reference to the accompanying drawings, in which

Fig. 1 is a diagrammatic plan view illustrative of display apparatus of a generally conventional type but embodying the present invention;

Fig. 2 is a fragmentary elevation of the front of a display apparatus showing a portion of the sight opening through which is seen the improved display band of the present invention;

Fig. 3 is an elevation of a flexible display element useful in the practice of the present invention, said element being of opaque material but having a light-transmitting area shaped to form a letter of the alphabet;

Fig. 4 is a section on the line 4—4 of Fig. 3;

Fig. 5 is a view similar to Fig. 3, but showing a display element of light-transmitting material having a relative opaque area in the shape of a letter of the alphabet;

Fig. 6 is a fragmentary elevation, partly in perspective, illustrating a preferred form of display band in accordance with the present invention;

Fig. 7 is a section on the line 7—7 of Fig. 6;

Fig. 7a is a view similar to Fig. 6, but to smaller scale, illustrating a band of a different kind of material;

Fig. 7b is a fragmentary section, similar to Fig. 7, illustrating a slightly modified construction;

Fig. 8 is a fragmentary plan view to larger scale than Fig. 1, showing the storage chamber portion 5 of the display apparatus and illustrating certain details of the improved means for moving the massed, inactive portion of the band through the storage chamber;

Fig. 9 is a fragmentary section on the line 9—9 10 of Fig. 8;

Fig. 10 is a fragmentary elevation of the parts shown in Fig. 8; and

Fig. 11 is a fragmentary end elevation of the parts shown in Fig. 8.

15 Referring to the drawings, the numeral 1 designates the casing of a display apparatus, such casing being, for example, of sheet metal comprising the end walls 2 and 3 and the elongate side walls 4 and 5. As here illustrated each of 20 the walls 4 and 5 is provided with a horizontally elongate display opening 6 and 7, respectively, although it is to be understood that but one of such display or sight openings may be employed.

As here shown, and for convenience in description, it is assumed that the apparatus will 25 be used in the horizontal position shown, but it is to be understood that the casing may be disposed so that the display openings are vertically elongate, or in any other desired position.

30 Adjacent to each corner of the casing, or at least at opposite ends of the respective sight openings, there are placed vertical guide rollers 7, 8, 9, and 10, respectively. Within the casing and spaced inwardly from the sight openings are 35 vertical light-diffusing elements 11 and 12, for example panes of frosted or faceted glass, it being understood that the sight openings themselves may be glazed, if desired, with plain or other glass, as preferred. Spaced inwardly from each 40 of the diffusing elements 11 and 12 there is disposed a source of illumination, such source consisting, for example, of a series of incandescent lamp bulbs 13, or a single elongate tubular lamp, or the like. The light source behind each of the 45 diffusing elements 11 and 12 is preferably housed within a reflector 14. As here illustrated the inner wall of each reflector takes the form of a substantially vertical partition 15, the space 16 between these partitions constituting a storage 50 chamber. Within this storage chamber, and parallel to one of the partitions 15 is a second partition 15b spaced a short distance from the adjacent partition 15.

55 Adjacent to the entrance end of the storage chamber 16 there is arranged a pair of vertical drive rollers 17 and 18, respectively, one of these rollers being provided with a pulley and being driven at a predetermined speed by means of a suitable motor device, for example an electric 60 motor 19, arranged within the casing. At the outlet end of the chamber there is preferably arranged a smoothing element, for example a brush 20, carried by a spring-pressed arm 21, and adjacent to the same end of the storage chamber.

65 Adjacent to the ends of the partitions 15 and 15b there is arranged a vertical guide roller 22, while at the opposite end of the same partition 15 there is preferably arranged a curved guide 23.

70 The flexible display belt 24, forming an essential feature of the present invention, passes around the guide rolls 7 and 8 to form a substantially straight run 24a which is exposed to the view of the observer through the sight opening 6. After leaving the guide roll 8 the band passes 75 between the driving rolls 17 and 18 which pull it

around the roll 8 and force it into the storage chamber 16 where it gathers in substantially vertical zigzag folds, to form a more or less compact mass M. At the opposite end of the storage chamber is arranged a deflector 25, designed 5 to keep the massed material from piling up against the pivoted end of the arm 21,—the band material being drawn out from the mass and passing out between the brush 20 and the partition 15b, the action of the brush being to smooth 10 out the folds of the band. The band then passes around the guide roll 22 and then along the narrow corridor between the partitions 15 and 15b and over the guide 23 and then about the roller 10, and thence to the roll 9, forming a substantially straight run 24b which is exposed through the sight openings 7. From the roller 9 the band extends to the roller 4, it being understood that the band is endless and that the runs 24a and 24b are ordinarily in constant motion across the sight 20 openings, preferably traveling from right to left.

In accordance with the present invention, a portion of the floor of the chamber 16 is formed by the upper substantially horizontal run of an endless belt conveyor 26. The floor proper F of 25 the storage chamber is furnished with an elongate opening which receives this belt conveyor 26. The lateral edges of this opening are defined by downwardly directed flanges 28 and 29, respectively, and at one end of the opening these flanges 30 are provided with guides for a sliding carriage 30 which supports a roller 31 about which the conveyor belt passes. This carriage is provided with a pair of sliding rods 33 embraced by springs 34 which tend to move the carriage to the right, 35 as viewed in Fig. 9, the carriage thus constituting tensioning means for the belt conveyor. At its opposite end the conveyor belt passes around a drive roll 32 which is journaled at its opposite ends in suitable bearings, the roll 32 being provided at one end with a worm wheel 35 which meshes with a worm 36 on the lower end of a drive shaft 31, having a drive pulley 38 at its upper end, and which turns in a vertical bearing post 39 projecting upwardly from the floor of the 40 casing. A belt (not shown) engaging the pulley 38, constantly drives the conveyor 26 so that the upper run of the conveyor moves from the entrance end of the storage chamber 16 slowly toward the other end, and in so moving supports 5 the major portion of the massed band material and assists in moving such material toward the outlet end of the storage chamber.

Referring to Figs. 2 to 7a inclusive, the improved display band 24, in accordance with the present invention, comprises flexible material such, for example, as cloth, strong paper, celluloid, thin flexible sheet material or the like. In the preferred embodiment of the invention, this band consists of two thicknesses 40 and 40a, respectively (Fig. 7), which are secured together in parallel slightly spaced relation. The two thicknesses 40 and 40a may initially be entirely separate, or they may consist of a single piece of material doubled longitudinally so that the two thicknesses are integrally united at the lower edge of the band. As illustrated in Fig. 7b, the band consists of two independent lengths of material united by a sewed seam 41 extending along their lower edges. Whether made of an integral piece of material folded, or of two independent pieces of material, the two thicknesses of the band are united preferably at regularly spaced intervals by transverse connecting elements such, for example, as sewed seams 42.

While sewed seams are useful in uniting the two thicknesses of the band material, it is to be understood that other means may be employed such, for example, as adhesive, and in particular if the band material be celluloid or the like, the union between the two thicknesses may be a substantially integral union such as may be formed by the application of a solvent to the band material at the desired points, accompanied by localized pressure and/or heat.

In whatever way the band be made and of whatever material, the union of the two thicknesses at spaced intervals as suggested forms a longitudinally extending series of pockets each adapted removably to receive a thin, flexible, display element. Such a display element 44 is illustrated in Fig. 3. This element may consist of any suitable flexible material thin enough to be slipped between the thicknesses 40 and 40^a of the band. For this purpose thin but tough paper or celluloid have both been found useful. As illustrated in Fig. 3, the element 44 comprises a substantially opaque area 45 and a light-transmitting area 46, the line 47 of demarcation between these areas defining the outline of a letter of the alphabet. While the areas 45 and 46 may be opaque and light-transmitting, respectively, it is to be understood that these terms are not used in an absolute sense but that the relative light-transmitting and light-occluding characteristics of these areas may vary to any degree, and also that one of these areas may be of one color and the other of another color, each having certain light-transmitting qualities, and when herein-after opaque areas and light-transmitting areas are referred to, these terms are intended to be inclusive of the above variations.

In Fig. 5 another modification is suggested wherein the display element 44^a comprises a light-transmitting area 48 having an opaque area 49 which is in the form of the letter or other character, shape or symbol which it is desired to display.

As illustrated in Fig. 6, the material of each thickness 40 and 40^a, respectively, of the band is provided with areas (each of which may be of substantially the same size and shape as one of the respective pockets) each provided with a multitude of small light-transmitting openings 43 and 43^a, respectively. These openings are conveniently formed by punching the band (as by means of a gang punch or the like) after the two thicknesses of the band have been united, as above described, so that the openings 43 in one thickness will substantially register with the openings 43^a in the other thickness. While it is preferred, as just described, to limit the perforations substantially to the portions of the band which constitute the pockets since this conserves the strength of the band, it is contemplated that the entire band may be perforated, even including those portions in which the stitching seams 42 occur, although under such conditions it is preferable to stitch the bands together after they have been perforated.

While punched perforations are desirable, particularly when the perforations are made so as to register in the two thicknesses of the band, it is contemplated that the band may be formed with light-transmitting openings in other ways. Thus, for example, as illustrated in Fig. 7^a, the band 51 may consist of two thicknesses of coarse woven textile fabric such that light will pass through the interstices between the woven yarns. In the same way it is contemplated that textile

material such as knitted material or lace material may be employed for the same purpose, and if, as above suggested, the band be made of such material as celluloid (which may be inherently of light-transmitting character) it may not be necessary to form any perforations whatsoever in the band. Likewise, it is contemplated that the several pockets may be made as individual elements and flexibly united, as by lacing, to form an endless band.

Having prepared a band as above described, together with a set of the display elements such as the elements 44, and having mounted the band in the casing so as to pass around the various guide pulleys, it is merely necessary to slip the proper display elements 44 into successive pockets of the band to build up the desired sequence of letters and words to form any desired advertising sign, slogan, notice or the like, it being obvious that the display elements may bear any distinctive characters desired, as well as letters of the alphabet. In order to prevent the display elements from working up out of the pockets by reason of the flexing of the band, it may be desirable to provide the open tops of the pockets with temporary closure devices. Thus, for example, a strip of adhesive tape 50 may be folded and arranged to straddle the upper edge of the belt at the top of each pocket after the insertion of the display element, although any other suitable type of fastener may be employed.

As the material of the belt is pulled along by means of the drive rolls 17 and 18, it is delivered into the storage chamber 16, gradually building up a mass M therein, the lower edge of the band resting upon the conveyor belt 26 which, as above described, slowly moves the mass toward the delivery end of the chamber. Since the pull of the rollers 17 and 18 tensions the band throughout the runs 24^a and 24^b as well as that portion of the band which extends through the corridor between the walls 15 and 15^b,—the band is slowly drawn out from the delivery end of the storage chamber between the brush 20 and the partition 15^b and all wrinkles and folds are smoothed out. Since the band is of double the usual thickness, it is stronger than the ordinary band, but by reason of the conveyor 26 the tension on the band need not be substantially greater for moving it around the guide rolls than that to which the ordinary band is subjected, and thus the band is far more durable than the ordinary single thickness band. Furthermore, since the display elements are removably supported by the band it is possible at any time to change the display without changing the band and without the necessity of punching new holes in the band. Moreover, this arrangement permits a much greater variation in display elements than when such elements must consist merely of perforations in a single thickness band, since, as above suggested, the display elements may readily be made of different colors and may be of contours or of intricate patterns such as could not well be made merely by punching out openings in a single thickness of material. However, since the perforations 43 and 43^a in the band are substantially uniformly distributed, having no definite distinctive outline in themselves, the interposition of the display elements 44 between the two thicknesses of the band occults the light which would normally be transmitted through the small closely spaced perforations of the band to form a somewhat diffused lighted area, thus providing a very pleasing effect and affording a display apparatus

having unique characteristics and which is far more desirable than those at present available.

While certain desirable embodiments of the invention have been illustrated by way of example, it is to be understood that the invention is not necessarily limited to these precise embodiments but is to be regarded as broadly inclusive of any and all equivalents which fall within the scope of the appended claims.

10 I claim:

1. A flexible band for use in display apparatus of the kind in which a casing has a sight opening across which a run of the band is moved, and a storage chamber in which an inactive portion of the band is temporarily stored, said band comprising two thicknesses of material, each thickness having a multitude of small light-transmitting openings therethrough, each opening in one thickness of the material substantially registering with the corresponding opening in the other thickness, the band being constructed and arranged to support display elements between the two thicknesses of the band material.

2. A band for use in display apparatus of the class described, said band comprising two thicknesses of thin flexible material, means uniting the two thicknesses along their lower edges and also at spaced intervals transversely so as to form a series of pockets for the reception of thin, flexible display elements, the material of the opposite walls of each pocket being of light-transmitting type, and releasable closure means for the tops of the pockets.

3. A flexible endless band for use in display apparatus of the class described, said band being of flexible material and comprising two closely adjacent thicknesses, the two thicknesses of material being so united as to form a plurality of pockets extending as a series lengthwise of the band, each pocket having front and rear walls devoid of large openings, each pocket being designed to retain a thin, flexible display element, the material of the band being such as to permit

transmission of light through both walls of each pocket.

4. An endless band for use in display apparatus of the class described, said band comprising a length of flexible material transversely doubled to provide two thicknesses with a fold at the lower edge of the band, and means uniting the two thicknesses transversely at spaced intervals, thereby to form a series of pockets for the reception of removable display elements, the walls of each pocket each having a multitude of small uniformly distributed perforations therethrough, the perforations of the two walls substantially registering with each other.

5. A band for use in display apparatus of the class described, said band comprising two thicknesses of substantially opaque textile material, means uniting the two thicknesses along their lower edges, sewed seams uniting the two thicknesses, at intervals, transversely, to form a series of distinct pockets, each for the reception of a removable light-occulting element, the front and rear walls of each pocket each having a multitude of small light-transmitting openings therethrough, each opening of one wall substantially registering with the corresponding opening of the other wall.

6. In combination in display apparatus of the kind having a casing provided with a display opening and a source of illumination, an endless band having a run disposed between the source of illumination and the opening, and means for moving the band, the band being of flexible material, said band consisting of two thicknesses of substantially opaque material but having longitudinally spaced distinct areas each having a multiplicity of small light-transmitting openings in both thicknesses of the material, and flexible display elements each disposed between the thicknesses of the band and each of such a character as to modify light passing through the apertures in the band.

JOSEPH TADDONIO.
